UNITED STATES PATENT OFFICE.

JOSIAH WILSON MCADAM, OF VANCOUVER, BRITISH COLUMBIA, CANADA.

PAPER FASTENER.

Original application filed February 9, 1924, Serial No. 691,754. Divided and this application filed February 28, 1925. Serial No. 12,290.

This invention relates to paper fasteners, and especially to that class of fasteners used for holding drawing paper or tracing paper or linen down in proper position on drawing boards, the present application being a divisional application of the one filed by me on February 9, 1924, Serial No. 691,754, for a drawing board.

The object is to provide a simple, cheaply manufactured and strong and durable device which may be easily formed by stamping the parts from sheet metal, or the proper non-corrosive, non-rusting kind, and which may be readily installed in position in the surface of said board, as a permanent attachment thereof, to be easily and quickly opened for the reception of the proper edge of the paper, or other material, and as easily closed to penetrate and hold the same in proper, square position with relation to the board.

Another object is to provide a fastener of this class having a minimum number of coacting parts, connected together for operation in a manner to prevent their accidental separation, and to provide simple means for retaining the device in countersunk position in the board, with the exposed surfaces of the parts lying flush with the surface thereof, except the paper engaging member, which may be easily detached from the paper by the finger nail.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:—

Figure 1 is a plan view of a portion of a drawing board having the improved paper fastener applied thereto and shown in the act of holding a sheet of paper.

Figure 2 is a transverse sectional view taken substantially on the line 2—2 of Figure 1, and drawn on a larger scale.

Figure 3 is a longitudinal sectional view of the subject matter of Figure 2, the paper holding member being in depressed position.

Figure 4 is a view similar to Fig. 3, the paper holding member being raised as for the reception or release of the paper.

Figure 5 is a vertical, transverse section taken on the line 5—5 of Figure 3.

Figure 6 is a view similar to Figure 5, of a slightly modified form of the invention.

Figure 7 is a fragmentary plan view showing another modification of the invention properly mounted in the board.

Figure 8 is a longitudinal sectional view of the same, the paper holding member being shown in position for engaging and holding the paper.

Figure 9 is a view similar to Figure 8, the holding member being elevated to receive or release the paper.

While the different forms of the paper fastener have been illustrated in the drawing as being applied to a board having the characteristics of the board shown and described in the above-mentioned parent case, it must be understood that the invention may be as easily applied to and used with equal advantage in connection with an ordinary drawing board, having a plain, smooth, uninterrupted working surface, such as are in common use.

As illustrated in Figures 1 to 5 inclusive, the invention comprises a metallic casing, preferably formed of thin sheet brass of a proper length and bent longitudinally to provide spaced side walls 1 and 2 respectively, of elongated, rectangular form, as viewed from the side, and joined together by a bottom wall 3 formed integrally therewith and co-extensive with the length of the same.

The casing is adapted to be inserted in a proper, pre-formed slot or kerf 4 formed in the board at the proper distance from the lefthand side edge thereof, it being understood, of course, that the fasteners are used in duplicate ordinarily, and that there is a slot or kerf for each fastener, though in the case of very large boards for making large plans or working drawings, etc., or for tracing the same, the fasteners may occur at more frequent intervals in longitudinal alignment with each other and arranged vertically on the board.

One of the walls of the casing, say the wall

1, which is located adjacent to the lefthand side edge of the board, is provided adjacent to one end thereof, preferably the end adjacent to the lower edge of the board, or 5 that edge closest to the draftsman, with an inwardly directed pivotal point 5, which is preferably formed by indenting the said wall from the outside thereof, or puncturing the same to provide one or more projections of the sheet metal, said projections extending towards the opposite wall of the casing to provide the aforesaid pivot.

10 Adjacent to the opposite or upper ends of each side wall the metal is punched outwardly, during the process of forming the casing and prior to placing the same in the slot or kerf, as clearly shown in Figure 2 of the drawing to form outwardly directed prongs 6, extending from either side of the 15 casing and adapted to engage the opposite walls of the slot or kerf 4 and to penetrate the wood of the board to hold the casing in position in said slot or kerf, in order to prevent accidental displacement of the same.

20 The casing may be introduced endwise into the slot or kerf or in an inclined position with the prongs 6 at a distance from their positions when fully seated, and by moving the casing longitudinally within the 25 kerf, the opposite end of the same may be forced down into position with both ends properly seated. The prongs will, when thus forced, form a transversely disposed or inclined entrance groove in the sides of 30 the kerf and also longitudinal grooves therein, but the same will soon become partially closed, owing to the nature of wood, and said entrance grooves, being remote from the prongs, when the casing is fully seated, 35 will not permit the accidental dislodgment of the casing from within the kerf. In some instances it may be deemed advisable to dispense with the prongs and to hold the casing in the kerf by means of glue or shellac.

40 45 Mounted to rock upwardly and downwardly within the casing, is a swinging tongue or lever 7, likewise formed of sheet brass or some other metal having similar qualities, said lever being somewhat shorter than the casing and of substantially the same width as the walls 1 and 2. At one 50 end the lever 7 is provided with an aperture 8, into which is adapted to extend the aforesaid pivotal point 5, the lever being held thereon by the engagement with the sides 55 of the casing.

60 With the lever thus mounted between the side walls 1 and 2, the bottom edge of said lever is close to and parallel with the bottom wall of the casing and when the lever is depressed, the upper edge of the same is flush with the upper edges of the said walls. The opposite end of the lever is provided 65 with an integral, laterally extending arm 9 bent at right angles to the lever and adapted

70 to extend out over the adjacent portion of the drawing board, the arm 9 having an integral, terminal prong or point 10 depending therefrom and adapted to be seated in a recess 11 formed in the board for the reception of the same when the lever is fully depressed. The edge of the said arm 9 located at the terminal of the lever is turned slightly upward, as at 12, to form a finger hold to be engaged by the finger nail for 75 raising the lever, as indicated in Figure 3 of the drawing. When the lever is thus raised, the edge of the paper 13, as shown in Figure 2, may be inserted thereunder, the point of the prong being then free of the 80 recess 11, and by inserting the paper far enough to contact with the body portion of the lever, the said paper may be easily trued or squared on the board, when the lever is forced downwardly between the side walls 85 and the prong caused to penetrate the paper and to be seated in the recess.

90 In Figure 6 of the drawing there is shown a simplified form of the above described fastener in which the casing is entirely eliminated, and the lever 14 provided with the arm 15, prong 16 and finger hold 17, similar to the first described form, is embedded directly in a slot or kerf 18 formed in the drawing board, the same being of a width to 95 freely receive the lever which is provided with a laterally directed prong 19 formed by punching, which may act as a pivot in an obvious manner. In seating the lever 14 in the said kerf, the end having the 100 prong thereon may be introduced endwise into one end of the kerf and in an upstanding position, and then forcing the prong longitudinally along the kerf to the proper point when the lever may be swung downwardly 105 to lie entirely within the kerf, and the prong will effectually serve as a pivotal point and at the same time prevent the lever from becoming detached. In like manner the aforesaid casing having the side walls 1 and 2 110 may be introduced into the slot or kerf as before described.

115 A further modification of the invention is shown in Figures 7, 8 and 9 wherein the casing is in the form of a hollow boxing 120 adapted to be seated into a rectangular seat 20 formed in the upper face of the board 21. This boxing comprises a bottom plate 22, an end plate 23 and a top plate 24, the latter having an integral, centrally disposed, depending tongue 25. The top plate 24 is provided with a central aperture 26 through which a screw 27 may be introduced to traverse a screw hole 28 formed in the bottom plate, and to enter the board for 125 holding the casing in position within the seat 20. A swinging plate 29 equal in width to the top plate of the casing is hinged to the boxing 130 by means of a transverse slot 30 formed therein, and adapted to re-

ceive the aforesaid depending tongue 25, the inner edge of the plate or that portion lying beneath the top plate of the casing, being bent at an obtuse angle to provide the inclined leg 31 which extends downwardly and inwardly and contacts with the upper face of the bottom plate of the casing. When the associated parts are in the position shown in Figures 7 and 8, with the swinging plate, which is, in substance, the equivalent of the aforesaid swinging lever 7, in horizontal alinement with the top plate of the casing, the said leg is at an angle, and when the plate or lever 29 is raised, the hinged engagement of the two parts causes the top plate to flex or bend upwardly, as shown in Figure 9, thus causing a strong downward pressure on the leg 31 which has been brought to a vertical position and is thus held with the free end of the lever 29 elevated above the surface of the board. The free end of the lever is provided with a depending prong 32 and is also preferably rounded as shown, the sides of the rounded portion being undercut, as indicated in dotted lines in Fig. 7, to serve as finger holds 33 for engagement by the finger nail in order to elevate the lever and free the prong from a corresponding recess 34 formed in the surface of the board.

The board is preferably provided with a depression 35 extending from the top to the bottom edges thereof, the opposite wall of which is formed on a gradual incline 36 so as to avoid creasing the paper or linen, and also to allow the blade 37 of a T-square (as shown in dotted lines in Fig. 2) to freely pass over the fasteners, as the same is shifted up and down on the board during the process of drawing.

From the foregoing it will be seen that a simple and cheaply manufactured paper fastener has been provided, which may be readily installed in drawing boards for the purpose of holding paper or linen for drawings or tracings, the same being easily operated to engage and hold the material, or to release the same, there being no delicate

parts to become broken or detached and lost. What is claimed is:

1. A paper fastener for drawing boards, comprising a metallic casing adapted to be countersunk in the board with its upper face flush therewith, a lever fulcrumed at one end in the casing and adapted to be swung up or down, said lever having a pin to puncture and hold the drawing paper. 50

2. A device for fastening paper or the like on drawing boards, comprising a casing having its upper face substantially flush with the surface of the board, a lever hinged at one end to the said casing and adapted to be swung toward or away from the board, means for holding the casing in the board, a finger hold formed on the lever, and a pin carried by the lever to puncture and hold the paper or the like. 60

3. In a drawing board, a paper fastening means, comprising a casing embedded in the board and open at the top, a vertically-swingable lever fulcrumed at one end in the casing and having an arm at the other end, said arm having a finger-hold, and a down-turned terminal pin entering a recess in the board and adapted to puncture the paper 75 to hold the same in position. 70

4. A paper fastener for drawing boards, comprising a U-shaped casing embedded in the board with the open side of the casing flush with the surface of the board, outward projections carried by the walls of the casing and entering the board to prevent the dislodgment of the casing, an inwardly directed projection carried by one of the walls near one end of the casing, a vertically swinging lever having an opening at one end to receive said projection to fulcrum said lever between the walls of the casing, said lever having an overhanging arm terminating in a depending pin for puncturing the edge of the drawing paper when the lever is pressed down into said casing. 80

In testimony, that I claim the foregoing as my own, I have hereto affixed my signature.

JOSIAH WILSON McADAM.
